CLAIM

The ornamental design for a solar generator, as shown and described.

DESCRIPTION

FIG. 1 is a front elevational view of a solar generator showing my new design;

FIG. 2 is a top plan view thereof; and

FIG. 3 is a bottom plan view thereof;

FIG. 4 is a top front perspective view thereof, other views from various sides being identical due to the symmetrical nature of the design.

FIG. 1

FIG. 2

FIG. 3

FIG. 4
